(57) **CLAIM**

I claim the ornamental design for a “pedal board,” as shown and described.

DESCRIPTION

FIG. 1 is a perspective view of a pedal board;
FIG. 2 is a front view of the pedal board;
FIG. 3 is a back view of the pedal board;
FIG. 4 is a top view of the pedal board;
FIG. 5 is a bottom view of the pedal board;
FIG. 6 is a right side view of the pedal board; and,
FIG. 7 is a left-side view of the pedal board.
Broken lines illustrate environmental features and form no part of the claimed design.
